UNITED STATES PATENT OFFICE.

CHARLES W. GASTON, OF ALLEGHENY, PENNSYLVANIA.

COMBINED PENCIL SHARPENER AND HOLDER.

SPECIFICATION forming part of Letters Patent No. 780,032, dated January 17, 1905.

Application filed March 30, 1904. Serial No. 200,740.

To all whom it may concern:

Be it known that I, CHARLES W. GASTON, a citizen of the United States, residing at Allegheny, in the county of Allegheny and State 5 of Pennsylvania, have invented a new and useful Improvement in a Combined Pencil Sharpener and Holder, of which improvement the following is a specification.

This invention relates to an improved combined pencil sharpener and holder; and it consists in the certain details of construction and combination of parts, as will be fully described hereinafter.

In the accompanying drawings, Figure 1 is 15 a perspective view of my improved pencil sharpener and holder, the same being constructed and arranged in accordance with my invention. Fig. 2 is a side elevation of the same, showing the position of the parts when 20 folded.

To construct a device in accordance with my invention, I provide a thin sheet-metal tube 1 of a suitable length and diameter and arrange in one end thereof a soft-rubber eraser 2. Formed near the top of the tube 1 are slots 3, the one directly opposite to the other and adapted to receive the hooked ends 5 of a portion 25 consisting of a semicircular end 7, the two arms 4, the one parallel to the other and terminating in the above hooked ends 5. Intermediate of these arms 4 and forming a part of the semicircular portion 7 is a sharpened edge forming a knife 6, whereby a point may 30 be made on the pencil 8. This swinging knife portion above described may be folded close to the holder 1, as shown at Fig. 2 of the drawings, and confined in that position by an integral tongue 9, formed by slotting the holder, as at 11. Beneath this tongue 9 is another, 35 bent slightly inward to make a frictional contact with a pencil 8 inserted in the tube 10 and hold the same therein.

To sharpen or form a point on a pencil, the implement is held in the left hand and the pencil 8 inserted in the position shown in dotted lines at Fig. 1 of the drawings and drawn back and forward over the knife 6. 45

To fold the device, the knife portion is brought in contact with the holder and moved forward in the direction of its length, thereby 50 moving the portion 7 beneath the tongue 9, as will be seen by reference to Fig. 2 of the drawings.

Various slight modifications and changes 55 may be made in the details of construction without departing from the spirit of the invention. Therefore I do not wish to confine myself to that shown and described.

Having thus described my invention, what I claim, and desire to secure by Letters Patent, is—

The herein-described combined pencil sharpener and holder, consisting of a tube or holder open at each end adapted to receive an eraser and pencil, slots formed lengthwise in either 65 side of said tube, the one opposite to the other, the spring-tongues 9 and 10 integral with said tube, the one 9 bent outwardly to form a keeper and the other 10 bent inwardly to hold an inserted pencil, in combination with a pencil-sharpener, consisting of a semicylindrical portion 7, the inner edge of which is sharpened 70 to form a knife 6, and integral paralleled arms 4, provided with inwardly-projecting hooks 5, to engage with the slots of the said tube, 75 all arranged and combined, substantially as described.

In testimony whereof I have hereunto signed my name in the presence of two subscribing witnesses.

CHARLES W. GASTON.

In presence of—

FRED O. HENZI,
H. J. LEVIS.
